UNITED STATES PATENT OFFICE.

THOMAS F. HANWAY, OF CHICAGO, ILLINOIS.

SPARK-PLUG.

1,334,698.

Specification of Letters Patent. Patented Mar. 23, 1920.

Application filed May 12, 1917. Serial No. 168,251.

To all whom it may concern:

Be it known that I, THOMAS F. HANWAY, a citizen of the United States, residing at Chicago, in the county of Cook and State 5 of Illinois, have invented a certain new and useful Improvement in Spark-Plugs, of which the following is a specification.

This invention relates to spark plugs for internal combustion engines, and has for 10 its object to provide a new and improved device of this description.

The invention is illustrated in the accompanying drawings, wherein—

Figure 1 is a sectional view showing a 15 spark plug embodying the invention.

Fig. 2 is a plan view of one of the electrodes before being bent into form.

Fig. 3 is a side view of the electrode shown in Fig. 2 after being completed.

Fig. 4 is a sectional view of the lower end 20 of the plug showing the seating groove for holding one of the electrodes.

Like numerals refer to like parts throughout the several figures.

In carrying out my invention I provide 25 a body portion or shell 1 of the plug, which is of metal and to which one of the electrodes is connected, the body portion being threaded to engage a threaded opening in the cylinder. An insulating piece or core 2 is provided, and a metallic rod 3 extends through this insulating piece, the lower end forming the other electrode of the plug. I prefer to split this lower end into several 30 pieces 4, as shown. The insulating piece 2 is held in place by the nut 5 which engages threads in the body portion 1. The body portion is provided with a shoulder 6 and the insulating piece has an enlargement 7 which engages this shoulder, and which is 35 also engaged by the nut 5. I prefer to provide washers 8 and 9 between the enlargement 7 of the insulating piece and the nut 5 and shoulder 6. The rod 3 is threaded 40 and is held in place by the part 10 and the end fittings 11 and 12. One of the electrodes is made removable without taking the plug apart, and consists of a ring 13 having supporting arms 16 projecting therefrom and 45 terminating in cross pieces 17 which engage the inner wall of the body portion 1. The body portion 1 is provided with longitudinal 50 grooves or recesses 18 intersecting a circumferential groove or recess 19 adapted to receive these supporting arms 16 and cross

pieces 17, the cross pieces 17 fitting into the groove or recess 19. This removable electrode may be made in any desired manner, but I prefer to stamp it out of a single piece of metal and then form it into the shape illustrated in Fig. 3 by drawing the metal into the proper shape. It will thus be seen that by means of this device one of the electrodes may be easily and quickly placed into position by forcing the engaging parts up into the body portion, said engaging parts automatically springing into their seating groove when they reach the proper position. It will thus be seen that this electrode is detachable and is provided with means for automatically attaching it to the body portion. It will further be seen that this electrode can be easily and quickly removed for cleaning purposes or for any other purpose. The parts 4 form a plurality of points for the other electrode, and the ends of all of them are in proximity to the ring portion 13 of the other electrode.

One of the great troubles with spark plugs is that oil, used for oiling the cylinder, gets on the electrodes and prevents the operation of the plug. By means of my device this is entirely obviated because since there are four central points on the vertical electrode and the other electrode is circular, it will be seen that oil coming down the central electrode will not get on all the points and hence, one of the points will be sure to act and then at the explosion, such oil will be burned off.

I claim:

1. A spark plug, comprising a body portion, an insulating piece disposed therein, a metal rod extending through said insulating piece, the end thereof forming one electrode, said body portion being provided with a circumferential internal groove near the inner end thereof and with longitudinal grooves extending from said internal groove to the inner end of the plug, a second electrode comprising a metal ring, arms connected with said ring and adapted to fit in said longitudinal grooves, and engaging devices connected with the ends of said arms and adapted to fit into said circumferential groove.

2. A spark plug, comprising a body portion, an insulating piece disposed therein, a metal rod extending through said insulating piece, the end thereof forming one elec-

trode and being formed into a plurality of points, said body portion being provided with a circumferential internal groove near the inner end thereof and with longitudinal grooves extending from said internal groove to the inner end of the plug, a second electrode comprising a metal ring, arms connected with said ring and adapted to fit in said longitudinal grooves, and engaging devices connected with the ends of said arms

and adapted to fit in said circumferential groove.

In testimony whereof I affix my signature in the presence of two witnesses this 5th day of May, 1917.

THOMAS F. HANWAY.
